June 14th.

United States Patent Office.

GARRETTSON SMITH AND HENRY BROWN, OF PHILADELPHIA, PENNSYLVANIA,
ASSIGNORS TO SHARP AND THOMSON, OF SAME PLACE.

Design No. 3,554, dated June 15, 1869; antedated May 25, 1869.

DESIGN FOR A STOVE.

The Schedule referred to in these Letters Patent and making part of the same.

To all it whom may concern:

Be it known that we, GARRETTSON SMITH and HENRY BROWN, of the city of Philadelphia, in the State of Pennsylvania, have invented or produced a new and original Ornamental Design for a Stove, which we name "Star;" and we do hereby declare that the following is a full, clear, and exact description of the same, reference being had to the accompanying drawings, making a part of this specification, and to the letters of reference marked thereon.

Our said invention or production consists in the

bas-relief ornamental figures on the plates *a a, b, c, d*, as shown in the drawing.

What we claim as our invention or production, and desire to secure by Letters Patent, is—

The bas-relief ornamental figures on the respective plates *a a, b, c, d*, as shown and described, as a design for a stove.
